UNITED STATES PATENT OFFICE.

MICHAEL NOULETT, OF NEW YORK, N. Y.

DESIGN FOR A LADY'S COLLAR.

SPECIFICATION forming part of Design No. 17,692, dated September 6, 1887.

Application filed July 13, 1887. Serial No. 244,224. Term of patent 7 years.

To all whom it may concern:

Be it known that I, MICHAEL NOULETT, of the city of New York, county and State of New York, have invented and produced a new and original Design for Ladies' Collars, of which the following is a specification, reference being had to the accompanying drawings.

Figure 1 is a perspective view of my newly-designed lady's collar. Fig. 2 is a vertical section through the same on line $x x$, Fig. 1.

This invention relates to a lady's collar of pleasing appearance; and the leading feature of the design consists of a number of ruffles projecting upwardly from a binding and ornamented by a number of jewels placed at equal distances apart.

$a a'$ represent a pair of ruffles projecting upwardly from the binding b . From the front ruffle there project forwardly a number of jewels, c , which give to the collar a brilliant and striking appearance.

What I claim is—

The design for a lady's collar, consisting of ruffles $a a'$, and of binding b , and of the jewels c , projecting forward from the plane of the ruffle, substantially as shown.

M. NOULETT.
